UNITED STATES PATENT OFFICE.

JOSEPH WATSON, OF EVERETT, MASSACHUSETTS.

IMPROVEMENT IN PRINTING-PRESSES.

Specification forming part of Letters Patent No. 133,959, dated December 17, 1872.

To all whom it may concern:

Be it known that I, JOSEPH WATSON, of Everett, in the county of Middlesex and State of Massachusetts, have invented certain Improvements in Printing-Presses, of which the following is a specification:

My invention relates to the combination of lever, connecting-rods, and toggle-joint with the treadle.

Figure 1 is a top view, embracing my invention. Fig. 2 is an elevation of Fig. 1. Figs. 3 and 4 are transverse sections.

A³, the frame; B³, the bed; C³, the platen; D³, connecting-bars; E³, hand-lever; F³, treadle; J³, toggle-joint; all of which require no further specification. g⁴ and i⁴ are arms, inserted in disk j⁴. k⁴ is a weight hung on arm i⁴. This disk has a notch cut in its upper edge. h⁴ is a pawl, with notch fitting into notch in disk.

The within-described printing-press, being constructed as herein shown, with hand-lever, toggle-joint, treadle, and connecting-bars, its operation may be noted. The paper to be printed is placed on the platen, and rests on arm g⁴. (See Fig. 4.)

The above-named devices having been used separately in hand printing-presses, their dimensions and mechanical constructions being so well known, any mechanic skilled in the art to which they appertain will be enabled to

construct them, when combined as herein shown, without further specification.

By pressing down the hand-lever with the right hand, and at the same time pressing down the treadle with the right foot, the platen approaches the bed with great force by the combined action of hand-lever, toggle-joint, connecting-bars, and treadle, as will be observed without further specification. When the hand-lever and treadle are raised, the disk j⁴, moving with the platen, is held by catch h⁴, attached to frame, till the platen recedes some distance from the bed, when the paper drops below the platen. The notch in the disk slips from the notch in the pawl, and the weight on the arm causes the bar or arm g⁴ to rest on the platen, assuming position shown in Fig. 3. When the desired impression on the paper is attained adjusting-screw m⁴ prevents too great pressure and damage to the type by contact with the arm D⁴.

In this invention I do not claim the hand-lever, connecting-bars, or treadle, separately considered; but—

I claim—

In combination, lever E³, connecting-rods D³ D⁴, toggle-joint J³, with treadle F³, as shown.
